UNITED STATES PATENT OFFICE.

CLARENCE C. BALDWIN, OF SEATTLE, WASHINGTON.

ADJUSTABLE NECKBAND FOR SHIRTS.

1,119,217.

Specification of Letters Patent.

Patented Dec. 1, 1914.

Application filed February 7, 1913. Serial No. 746,955.

To all whom it may concern:

Be it known that I, CLARENCE C. BALDWIN, citizen of the United States, residing at Seattle, in the county of King and State 5 of Washington, have invented certain new and useful Improvements in Adjustable Neckbands for Shirts, of which the following is a specification.

This invention relates to neck bands for 10 men's shirts and has as its object to provide a neck band the size of which may be increased or diminished to suit the wearer of the shirt or to provide for the attachment of collars of different sizes.

15 The invention has in view the provision of a neck band which forms a component part of the shirt and which may be adjusted as to size so that a dealer in shirts provided with the neck band will not be required to keep in stock a number of sizes of 20 shirts of a different style, but all of the shirts of any one style may be of the same size and adapted, by reason of the adjustability of the neck band, to fit different persons and for the attachment of collars of 25 various sizes.

Another aim of the invention is to so construct a neck band that it will automatically adapt itself to the neck of the wearer of the 30 shirt and will be automatically increased or diminished in size as the collar is being buttoned thereto.

It is a well known fact that it is a difficult matter to button a collar which is of 35 the same or smaller size than the neck band to which it is to be applied, for there is a tendency for the neck band to buckle thereby not only rendering the same uncomfortable but liable to work beneath the edge of 40 the collar.

The present invention therefore aims to so construct the neckband of a shirt that as the collar is being buttoned at the front, the neckband will be automatically contracted 45 to permit of readily and conveniently fastening the collar.

A further aim of the invention is to provide an adjustable neck band for shirts so constructed that the appearance of a shirt 50 will not be detracted from, and expansion or contraction of the neck band will result in corresponding expansion or contraction of the shoulder portions of the shirt.

Another object in view is to provide a 55 neck band which, upon the removal of the shirt collar, will automatically expand or

become loosened so as to become comfortable to the wearer and render unnecessary the unbuttoning of the top button of the shirt for comfort.

In the drawings: Figure 1 is a perspective view of a shirt equipped with the neck band embodying the present invention; Fig. 2 is a fragmentary view in side elevation thereof; Fig. 3 is a group perspective view illustrating the manner of assembling the adjustable sections of the neck band.

In the drawings, the front or bosom of the shirt is indicated by the numeral 1 and back by the numeral 2, the front and back being united at the shoulders of the shirt by the usual shoulder seam 3, which, however, is folded in a manner the reverse of that found in shirts as ordinarily made. From the neck line, the seam 3 is left open for a distance of several inches, more or less, as indicated at 4, and the shoulder portions of the back 2 being extended beneath the shoulder portions of the front 1, as indicated at 5, so as to form gussets which close the open portion 4 of the seam 3. At this point it will be apparent that the shirt at the neck line may be expanded or contracted.

The neck band of the shirt is formed in three sections, one section being secured to the back 2 at the neck line thereof and the other sections being secured to the sides of the bosom 1 at the neck line. The first-mentioned section of the neck band is indicated by the numeral 6 and is preferably of 40 four-ply structure, its plies being stitched together at their upper and lower edges except at a point midway between the ends of the section where the two outer plies are unattached to the two inner plies, and the said 45 outer plies are formed with a button hole 7. At each end the section 6 has its outer plies decreased in width for a distance of several inches, more or less, and these narrower portions of the outer plies constitute guide 50 strips 8 with which the other sections of the neck band are slidably connected, as will be presently pointed out. It will be seen that at the ends of the strip portions 8, the outer plies are secured to the inner plies by lines 55 of stitching 9. To the lower edge of the inner plies of the neck band 6 is stitched the upper edge of the back and the upper edges of the shoulder portions 2 thereof, the upper 60 edge of the gusset portion 5 being stitched to the said plies of the neck band section 6 at 65 points below the strips 8. Each of the other

70 75 80 85 90 95 100 105 110

sections of the neck band is indicated by the numeral 10 and each is provided at one end with a button hole 11. The other end of each of the sections 10 has fitted between its 5 plies the ends of a loop 12 which is of course of the same material as the remainder of the neck band. These loops 12 engage about the strips 8 and in this manner the neck band sections 10 are supported for sliding adjustment upon the section 6, and this adjustable connection of the three sections of the neck band will permit of expansion and contraction of the band, as will be apparent.

From the foregoing description of the invention it will be seen that there is provided an adjustable neck band for men's shirts which will automatically adapt itself to the neck of the wearer of the shirt and to the collar being worn. And it will further be seen that even when the neck band is expanded to its greatest extent, the open portion of the shoulder seams will be closed by the gussets 5 and the appearance of the shirt will not be detracted from, and furthermore 25 the shoulder portions of the shirt will adapt themselves to the wearer.

Having thus described the invention what is claimed as new is:—

1. An adjustable neck band for shirts consisting of a back section, guide strips secured to the outer face of the back section at the opposite ends thereof, each guide strip being secured to the back section by spaced rows

of stitching, the upper and lower longitudinal edges of the guide strips between said rows of stitching being cut-away to form a longitudinally disposed loop of less width than the back section, and end sections having transverse loops secured to the inner faces thereof at the rear ends of said end sections and embracing the guide strips forming the longitudinal loops, said transverse loops by engagement with the ends of the longitudinal loops serving to limit the expansion and contraction of the neck band. 45

2. An adjustable neck band for shirts consisting of a back section formed of a plurality of plies, the outer plies having portions thereof free of the inner plies and having their upper and lower longitudinal edges cut-away to form longitudinally disposed loops of less width than the inner plies, said loops being connected at their opposite ends to the inner plies by spaced lines of stitching, front sections overlapping the 55 back section, and transverse loops secured to the rear ends of the front sections and embracing the longitudinal loops, the inner face of the back section and the outer faces of the front sections being unobstructed. 60

In testimony whereof I affix my signature in presence of two witnesses.

CLARENCE C. BALDWIN. [L. s.]
